W. H. HARRISON

GARMENT HANGER SUPPORTING MECHANISM FOR WARDROBE TRUNKS

Filed Jan. 18, 1924

W. H. Harrison

Stich. 3.

By Clarice O'Brien

Attorney

UNITED STATES PATENT OFFICE.

WADE H. HARRISON, OF PETERSBURG, VIRGINIA.

GARMENT-HANGER-SUPPORTING MECHANISM FOR WARDROBE TRUNKS.

Application filed January 18, 1924. Serial No. 687,051.

To all whom it may concern:

Be it known that I, WADE H. HARRISON, a citizen of the United States, residing at Petersburg, in the county of Dinwiddie and 5 State of Virginia, have invented certain new and useful Improvements in Garment-Hanger-Supporting Mechanism for Wardrobe Trunks, of which the following is a specification.

10 This invention relates generally to the art of wardrobe trunks and has more particular reference to the garment hanger supporting mechanism therefor, the primary object of the present invention being substantially the 15 same as in several other applications filed on even date herewith, that is, to substantially improve and simplify arrangements of this general character.

An additional object of this invention is 20 to provide a garment hanger supporting means for wardrobe trunks of the hinged top type wherein the means may be removed as a unit and associated with bracket elements secured to one of the walls of the 25 inner side of the door of a closet whereby the garments may be placed therein when the traveler has reached his destination.

A still further object of this invention is 30 to provide a specific form of garment hanger for use in conjunction with this particular type of hanger supporting means whereby trousers or skirts may be supported directly upon means to which other garments may be detachably associated or whereby the same 35 may be secured thereto in an unfolded position when the garment hanger supporting mechanism is positioned within a closet.

Yet another object is to provide in conjunction with said garment hanger supporting mechanism, means whereby the same 40 may be readily removed from the trunk and associated with the brackets in the closet in a quick manner.

With the above and other objects in view 45 as the nature of the invention will be better understood, the same comprises the novel form, combination and arrangement of parts hereinafter more fully described, shown in the accompanying drawing and 50 claimed.

In the drawing wherein like reference characters indicate corresponding parts throughout the several views,

Figure 1 is a fragmentary vertical trans- 55 verse sectional view of a wardrobe trunk

equipped with my improved garment hanger supporting mechanism.

Figure 2 is a vertical longitudinal sectional view thereof, taken substantially upon the line 2-2 of Figure 1 and looking in a 60 direction indicated by the arrows, and

Figure 3 is a front elevational view of the member rigidly secured to one of the walls or the inner side of the door of a closet whereby the garment hanger supporting 65 mechanism of the present invention may be positioned therein.

Now having particular reference to the drawing wherein there is shown a garment hanger supporting structure to be used in 70 conjunction with wardrobe trunks of the type embodying a casing 5 having at its upper end the usual hinged lid 6, it being well known in the art that said casing 5 of the trunk has a hinged front wall 7 whereby 75 ready access may be had to the garments supported therein and whereby the same may be easily removed therefrom.

My garment hanger supporting structure per se embodies the provision of a sheet 80 metal strap 8 secured within the casing 5 of the wardrobe trunk and specifically to the rear wall thereof directly at its upper edge, said strap being formed at its opposite ends with forwardly extending portions 9-9 that 85 have close contact with the side walls of the casing portion 5 and are rigidly secured thereto as is the main strap 8 through the medium of rivets or other suitable fastening means. 90

The strap 8 is provided at points adjacent its opposite ends with metal plates or brackets 10-10 that have their central portions struck forwardly as at 11-11 for providing pockets for the detachable reception 95 of sheet metal fingers 12-12.

Each of these fingers 12 is rigidly secured to the inner end of a forwardly extending horizontal bar 13 of a length considerably less than the depth of the trunk and to the 100 front end of each of which is secured a plate 14 of sheet metal.

The finger 12 of each bar 13 as well as the plate 14 at the front end thereof extends slightly above the bar for allowing a relatively U-shaped sheet metal bale 15 to be pivotally secured therebetween. Each of these bailes 15 is formed intermediate its ends with a finger hook 16 whereby when the lid of the trunk 6 is raised said bailes 15 110

may be swung to a vertical position for allowing the garment hangers 17 supported between the bars 13 to be entirely removed from the trunk for purposes hereinafter to be more fully described.

The type of garment hanger employed in conjunction with the present invention consists of a cross bar as shown in Figure 2, formed at its opposite ends with curved fingers 18-18 for engagement over the bars 13-13. Intermediate the ends of said bars and pendant therefrom is a sheet metal leg 19 that is formed at its lower end with a slot 20 for the reception of the usual metal hook 21 of a well known form of coat hanger 22. In addition to this, said cross bar carries adjacent its opposite ends pendant spring clasps 23-23 whereby after the hangers have been removed as a unit from the trunk, trousers, dresses or other articles of wearing apparel may be connected to the hangers through the medium of said clasps. It might be well to herein state that when the hangers are supported within the trunk it is necessary that dresses, trousers, etc., be hung over the cross bars of said hangers in order to allow the same to be so placed within the trunk as not to become wrinkled. The clasps 23-23 of each of the hangers include sheet metal jaws 24-24, Figure 1, that are pivotally secured together through the medium of a relatively long cross pin 25. Each of these cross pins 25 is formed at one end with a downwardly bent portion 26, while at its opposite end the same is bent upwardly as at 27 and then formed with an inwardly extending looped portion 28 whereby after the garments have been positioned between the jaws of the clasps the pins 25 may be drawn in a direction toward the left of Figure 2 through the medium of a downwardly bent portion 26 for obviously positioning the looped portion 28 between the jaws for thereby preventing the opening of the same and a consequent disengagement of the garments with respect to said clasps.

Adapted for use in combination with the

present garment hanger supporting means for wardrobe trunks is a horizontal arm 29 that is formed adjacent its opposite ends and 50 upon its upper edge with notches 30-30. This arm 29 is carried by a bracket plate 31 whereby the same may be rigidly secured within a closet, it being at once obvious that after the traveler has reached his destination, the entire number of garments within the trunk may be removed as a unit therefrom by disengaging the fingers 12-12 of the supporting bars 13-13 from the brackets within the trunk and this through the 60 medium of the bales 15-15, after which the hooks 16 of these bales may be engaged over the notches 30-30 in the horizontal bar 29 within the closet.

It will thus be seen that I have provided 65 a highly novel and efficient form of supporting means for garment hangers to be particularly associated with trunks of the wardrobe type, and even though I have herein set forth the most practical embodiment of the 70 invention with which I am at this time familiar, it is nevertheless to be understood that minor changes may be made therein without departing from the spirit and scope 75 of the appended claim.

Having thus described my invention, what I claim as new and desire to secure by Letters Patent, is:—

A garment hanger support comprising a bail member having parallel end portions, a 80 finger pivoted at the side of one of the end portions, a plate pivoted at the side of the other end portion of the bail member, said pivots being in alignment with each other and having their axes disposed parallel with the intermediate portion of the bail member, said finger being longer than the plate and a bar connected at its ends with the finger and the plate and being disposed parallel 85 with the aligned axes of the pivots and the intermediate portion of the bail member.

In testimony whereof I affix my signature.

WADE H. HARRISON.
